COMBINED WALLET AND POCKET SECRETARY

Ludwig S. Schlessinger, New York, N.Y., assignor to Bond Street Ltd., New York, N.Y., a corporation of
New York

Filed Nov. 20, 1964, Ser. No. 82,720

Term of patent 14 years

(Cl. D87—3)

FIG. 1 is a front perspective view of a combined wallet and pocket secretary, showing my new design, in closed condition;

FIG. 2 is a rear elevational view thereof;

FIG. 3 is a front perspective view thereof in open condition; and

FIG. 4 is another front perspective view thereof in open condition.

The broken-line showing of papers in the wallet in FIG. 4 is for illustrative purposes only.

I claim:

The ornamental design for a combined wallet and pocket secretary, as shown and described.
